UNITED STATES PATENT OFFICE.

LINUS WOLF, OF CHICAGO HEIGHTS, ILLINOIS.

WELDING-TOOL.

1,218,503.

Specification of Letters Patent.

Patented Mar. 6, 1917.

Application filed May 21, 1914. Serial No. 839,956.

To all whom it may concern:

Be it known that I, LINUS WOLF, a citizen of the United States, residing at Chicago Heights, county of Cook, State of Illinois, have invented an Improvement in Welding-Tools, of which the following description, in connection with the accompanying drawing, is a specification, like characters on the drawing representing like parts.

This invention has reference to devices for autogenous metal welding and devices for cutting metals in which use is made of the heat produced by burning a combustible gas thoroughly mixed with an oxidizing gas.

The invention has for an object to provide an improved tool of this character which may be conveniently manipulated.

20. The invention further has for an object to provide an improved mixing device in which the gas will be thoroughly mixed by being passed around deflecting plates and by being separated into small currents.

25. Another object is to provide auxiliary means for supplying an oxidizing gas when desired for the purpose of oxidizing the metal as it is melted.

Another object is to provide an improved safety check valve to prevent back-firing.

The nature and objects of the invention will more fully appear in the following specification and the accompanying drawings and the novel features will be particularly pointed out in the claims.

Referring to the drawings in which I have illustrated a selected embodiment of my invention;

40. Figure 1 is a view in elevation of the assembled device;

Fig. 2 is a similar view showing the device for supplying an oxidizing gas attached to the tool;

45. Fig. 3 is a sectional detail view of the main mixer;

Fig. 4 is a sectional detail view showing the manner of connecting certain parts of the mixer;

50. Fig. 5 is a detail view of a cylindrical tubular member;

Fig. 6 is a sectional detail view of a coupler;

Fig. 7 is a view in elevation of the same;

55. Fig. 8 is a sectional detail view of the valve;

Fig. 9 is a sectional detail view of one of the deflecting plates;

Fig. 10 is a sectional view of the primary mixing chamber taken on the line 10—10 of Fig. 11;

Fig. 11 is a sectional detail view of the primary mixing chamber taken on the line 11—11 of Fig. 10;

Figs. 12 and 13 are detail views of the disks positioned in the outlet of the primary mixer;

Fig. 14 is a detail view partly in section of the means for supplying an oxidizing gas in front of the nozzle;

Fig. 15 is a perspective view of a coupler;

Fig. 16 is a detail view showing guiding means for controlling the path of movement of the nozzle the pivot member being shown as rotated out of its true position for convenience in illustration; and

Fig. 17 is a detail view of the truck for guiding the nozzle.

The device shown in the drawing by way of illustration comprises a primary mixer 1, a principal mixer 2 and a nozzle 3. A flexible tube or hose 4 is provided to connect the primary mixer with the main mixer and a valve 5 is inserted adjacent the main mixer to provide convenient means to control the flow of gas.

The main mixer comprises a chamber which is provided with a series of members each having a number of small holes through which the gas must pass and a series of deflecting plates to cause the gas to change its direction frequently as it passes through the mixer. I have illustrated this mixer as comprising a main tubular member 6, which in the form shown is circular. Heads 7, 8 are provided at opposite ends of the tubular member and these heads are provided with inlet and outlet passages 75 and 76 respectively. Within the tube are arranged a series of small tubular cylinders 9, 10, 11. Each cylinder is provided at one end with a series of small holes 12. The cylinders 9, 10, 11 are connected by similar couplers 13, 14 which serve also as partitions and the cylinder 11 is connected to the head 8 by means of a coupler 15, and a short tubular member 16. Similar cone-shaped deflecting plates 17, 18, 19 are clamped at the ends of the cylinders and contact with the tubular member 6 in such manner as to form partitions to prevent the passage of gas along the tubular member.

90. The main mixer comprises a chamber which is provided with a series of members each having a number of small holes through which the gas must pass and a series of deflecting plates to cause the gas to change its direction frequently as it passes through the mixer. I have illustrated this mixer as comprising a main tubular member 6, which in the form shown is circular. Heads 7, 8 are provided at opposite ends of the tubular member and these heads are provided with inlet and outlet passages 75 and 76 respectively. Within the tube are arranged a series of small tubular cylinders 9, 10, 11. Each cylinder is provided at one end with a series of small holes 12. The cylinders 9, 10, 11 are connected by similar couplers 13, 14 which serve also as partitions and the cylinder 11 is connected to the head 8 by means of a coupler 15, and a short tubular member 16. Similar cone-shaped deflecting plates 17, 18, 19 are clamped at the ends of the cylinders and contact with the tubular member 6 in such manner as to form partitions to prevent the passage of gas along the tubular member.

95. The main mixer comprises a chamber which is provided with a series of members each having a number of small holes through which the gas must pass and a series of deflecting plates to cause the gas to change its direction frequently as it passes through the mixer. I have illustrated this mixer as comprising a main tubular member 6, which in the form shown is circular. Heads 7, 8 are provided at opposite ends of the tubular member and these heads are provided with inlet and outlet passages 75 and 76 respectively. Within the tube are arranged a series of small tubular cylinders 9, 10, 11. Each cylinder is provided at one end with a series of small holes 12. The cylinders 9, 10, 11 are connected by similar couplers 13, 14 which serve also as partitions and the cylinder 11 is connected to the head 8 by means of a coupler 15, and a short tubular member 16. Similar cone-shaped deflecting plates 17, 18, 19 are clamped at the ends of the cylinders and contact with the tubular member 6 in such manner as to form partitions to prevent the passage of gas along the tubular member.

100. The main mixer comprises a chamber which is provided with a series of members each having a number of small holes through which the gas must pass and a series of deflecting plates to cause the gas to change its direction frequently as it passes through the mixer. I have illustrated this mixer as comprising a main tubular member 6, which in the form shown is circular. Heads 7, 8 are provided at opposite ends of the tubular member and these heads are provided with inlet and outlet passages 75 and 76 respectively. Within the tube are arranged a series of small tubular cylinders 9, 10, 11. Each cylinder is provided at one end with a series of small holes 12. The cylinders 9, 10, 11 are connected by similar couplers 13, 14 which serve also as partitions and the cylinder 11 is connected to the head 8 by means of a coupler 15, and a short tubular member 16. Similar cone-shaped deflecting plates 17, 18, 19 are clamped at the ends of the cylinders and contact with the tubular member 6 in such manner as to form partitions to prevent the passage of gas along the tubular member.

outside of the cylinders. Oppositely disposed cone-shaped deflecting plates 20, 21, 22 are clamped at the opposite ends of the cylinders and are spaced from the tubular member at their outer edges. An additional 5 member at the right deflecting plate 23 is provided at the right hand end of the mixer as shown in Fig. 3 and this with the plate 20 is held in position against the end of the cylinder 9, by means of 10 a screw plug 24. Each of the couplers 13, 14 is provided with an annular groove as indicated at 25 and a series of holes 26 for the passage of the mixed gases. The coupler 15 is provided with a series of radial 15 holes for the same purpose. By this construction the gases are caused to pass through the mixer by a tortuous path and are several times divided into a large number of small currents by means of the cylinders and couplers which are provided with 20 the series of holes.

The outlet passages 76 in the head 8 are closed by a safety check valve 27 and this valve is urged toward its seat by means of 25 a spring 77 which is of just sufficient tension so that the pressure will be overcome by the pressure of the gases upon the valve. A cap 28 secured to the head 8 provides 30 convenient connection for the pipe 78 to which the nozzle 3 is connected and also 35 presents a chamber for the valve 27. The valve presents a considerable area so that if the gases back-fire the explosion will cause the valve to seat quickly thereby closing the outlets in the head 8 to prevent back-firing into the mixer.

The mixer in this form conveniently 40 serves as the handle of the tool and I prefer to provide a shield to protect the hand from the heat of the flame. I have illustrated this shield as comprising a metal shell 29, lined with asbestos as indicated at 45. This shell may conveniently be clamped between the cap 28 and the head 8.

45 A truck 31 provides means to guide the tool to hold the nozzle in the correct position relative to the work and is secured to the tool as by being clamped upon the tube 78 and secured to the shield as indicated 50 at 33.

The primary mixer 1 is somewhat similar to the main mixer in that it is provided with a plurality of members having small holes to divide the flow of gas into a large 55 number of small currents. This mixer comprises a main casting 34 having a circular mixing chamber 79. Inlets 35, 36 enter this chamber tangentially as indicated in Fig. 11. The inlets preferably are so positioned 60 that the gases entering through these inlets will be forcibly blown against each other so that an initial mixing will take place as they enter the chamber. The inlets may be made in any convenient way to provide attachment for pipes supplying the combusti- 65

ble and oxidizing gases respectively. A funnel shaped member 37 is secured to the casting 34 as by means of a coupling ring 38, and is preferably positioned to provide an axial outlet from the mixing chamber. In 70 the larger end of this funnel-shaped member are provided disks 39, 40. One of these disks is provided with a series of holes as indicated at 41 and the other consists of a fine mesh wire screen. In the form illustrated the disk 39 is positioned adjacent 75 the mixing chamber.

The flexible hose 4 is connected at its opposite ends to the respective mixers by a novel and efficient joint as illustrated most 80 clearly in Fig. 10. The funnel-shaped member is provided with a corrugated tubular projection 42 onto which the end of the hose is forced. A tapered sleeve 43 is screwed onto the funnel-shaped member to 85 securely clamp the end of the hose against the corrugated tubular projection 42. The hose is preferably provided with a protective armor, in the form of a wire 44, the end 80 of which projects into a hole in the 90 sleeve, thus securely anchoring the wire and holding it in position. A similar connection is provided at the other end of the hose.

The valve 5 is illustrated in Fig. 8. This valve comprises a casing 45 having an inlet 95 passage 46 and an outlet passage 47. The casing is provided with an annular portion 48, upon which a valve cap 49 is secured. A flexible diaphragm 50 is secured at its 100 edge to the annular portion 48 in such manner as to provide a gas tight joint. The escape of gas from the valve casing is therefore impossible even if the cap does not fit accurately. At the center of the annular portion a projection 51, in the center of 105 which is positioned the inlet passage, presents a smooth surface 52 upon which seats a disk 53, serving as a valve. A spring 54 urges this valve from its seat and means are provided to press against the flexible 110 diaphragm and thus force the valve to its seat to close the inlet. The means illustrated comprises a thrust block 55 and a thumb screw 56. It will be seen that I have thus provided a valve which will not 115 become leaky upon the wearing of the parts and a valve which does not depend upon the tightness of any packing to insure perfect operation.

I have illustrated in Fig. 14 an attachment for supplying an oxidizing gas in front of the nozzle. This attachment as 120 illustrated is designed to be secured to the main mixer and may easily be attached thereto upon removal of the hand shield. The nozzle 3 is attached to the tube connecting it with the mixer in such a manner that it may easily be removed to be replaced by a nozzle of larger or smaller bore. The oxygen supplying attachment consists of a 125 130

- 5 sleeve 57 which is designed to fit upon the nozzle and be clamped thereupon, a valve 58 for controlling the supply of oxygen and a flexible tube 59, to be connected with the supply of oxygen or other oxidizing gas. The valve illustrated comprises a valve casting 60; a valve 61 spring pressed toward its seat and an operating handle 62. A secondary nozzle 63 is secured to the sleeve and 10 preferably extends somewhat beyond the end of the nozzle, 3. A tube or pipe 64 connects this nozzle with the valve. The sleeve is secured in position upon the nozzle by means of a set screw 65.
- 15 Upon each side of the sleeve 57 are provided hubs 66—67 which are threaded to receive stud bolts. I may either attach a pair of wheels at these points or if it is desired to cut upon an arc I may attach one 20 wheel 68 and a radius arm 69. Adjustable upon this radius arm is a pivot member 70 which for the purpose of clearness is illustrated as rotated out of its operative position.
- 25 The operation of the device will be sufficiently clear to one skilled in the art, from the foregoing description, without further explanation. I contemplate various modifications as within the scope of my invention.
- 30 Having fully described my invention, what I claim as new and desire to secure by Letters Patent is:
1. A device of the character described comprising a primary mixer, a main mixer, a flexible tubular connection between said mixers, a nozzle connected to receive gas from said main mixer, and a safety check valve positioned between said main mixer and said nozzle.
  - 40 2. In a device of the character described a primary mixer comprising a circular chamber having tangentially entering gas inlets, a main mixer having a series of deflecting plates and means for dividing the flow of mixed gases into several small currents, a flexible tubular connection between said primary and main mixers, and a nozzle connected to said main mixer.
  - 45 3. In a device of the class described, a gas-mixing element comprising an outer tubular member, an inner member presenting a plurality of chambers, deflecting plates interposed between the inner and outer members and dividing the space between them into compartments, each chamber having communication with two adjacent compartments whereby the gases are compelled to pass through the compartments and chambers alternately.
  - 50 4. In a device of the character described, a mixer comprising an outer tubular member, heads at opposite ends thereof, an inner tubular member having a plurality of small holes near one end thereof to provide inlets and a plurality of small holes near the opposite end thereof to provide outlets, and a deflecting plate surrounding said inner tubular member and engaging said outer tubular member to cause all gases which pass through said outer tubular member to flow 65 through the inlet holes into said inner tubular member and out through the outlet holes thereof.
  - 55 5. In a device of the class described, a gas-mixing device comprising a chamber, a series of hollow elements within the chamber, each provided with a series of small inlet openings and a series of outlet openings, and deflecting plates interposed between said hollow elements and the walls of said chamber and constructed to cause the gases to pass successively through the hollow elements.
  - 60 6. In a device of the character described a mixer comprising a tubular chamber, a series of tubular members centrally positioned in said tubular chamber and each provided at opposite ends with a series of small holes, and a series of cone-shaped deflecting plates surrounding the tubular members of said series and positioned with their open ends toward each other, the larger ends of alternate tubular members fitting against the wall of said tubular chamber, the deflecting plates being so arranged that gases passing through said mixing chamber will pass around the outer edge of one cone-shaped deflecting plate through the small holes into the corresponding tubular member and out through the holes at the opposite end 75 thereof.
  - 65 7. In a device of the class described, a gas-mixing element comprising a circular chamber having two tangentially-disposed inlets situated at an angle to each other and entering the chamber closely adjacent each other, said chamber having an axially-disposed outlet and a perforated plate disposed in said outlet.
  - 70 8. In a device of the character described a mixer comprising a circular mixing chamber having a plurality of tangentially disposed inlets and having an axially disposed outlet, and a plurality of disks disposed across said outlet, one of said disks consisting of a perforated plate and the other disk consisting of a wire mesh screen.
  - 75 9. In a device of the character described, a primary mixer comprising a circular chamber having tangentially entering gas inlets, a main mixer having a series of deflecting plates and means for dividing the flow of mixed gases into several small currents, a connection between said primary and main mixers, and a nozzle connected to said main mixer.
  - 80 10. In a device of the class described, a primary mixer having provision for intro-

ducing two different gases thereto and for mixing said gases, a main mixer, a flexible tubular connection between said mixers and through which both gases are delivered to the main mixer, and a nozzle connected to the main mixer to receive gas therefrom.

In testimony whereof, I have signed my

name to this specification, in the presence of two subscribing witnesses.

LINUS WOLF.
